UNITED STATES PATENT OFFICE.

GEORGE GODDU, OF WINCHESTER, MASSACHUSETTS, ASSIGNOR TO UNITED SHOE MACHINERY COMPANY, OF PATERSON, NEW JERSEY, A CORPORATION OF NEW JERSEY.

SHANK-TRIMMING MACHINE.

1,018,045.

Specification of Letters Patent. Patented Feb. 20, 1912.

Application filed September 25, 1908. Serial No. 454,727.

To all whom it may concern:

Be it known that I, GEORGE GODDU, a citizen of the United States, residing at Winchester, in the county of Middlesex and State of Massachusetts, have invented certain new and useful Improvements in Shank-Trimming Machines; and I do hereby declare the following to be a full, clear, and exact description of the invention, such as will enable others skilled in the art to which it appertains to make and use the same.

The present invention relates to an improvement in shank trimmers.

Heretofore in the making of shoes it has sometimes been the practice to trim the edge of the sole from the seam outward, whereby the sole edge was made to appear thinner than the actual thickness of the sole.

The object of the present invention is to produce an improved machine for performing this operation.

The invention consists in the construction hereinafter described and particularly defined in the claims.

In the accompanying drawings illustrating the preferred form of the invention, Figure 1 is a side elevation of so much of the machine as is necessary to illustrate the construction of the operative parts, Fig. 2 is an elevation of the opposite side, Fig. 3 is a sectional elevation taken on the plane of the knife shaft, Fig. 4 is a front elevation, and Fig. 5 is a transverse sectional elevation.

The illustrated embodiment of the invention is described as follows:—The two principal elements of the machine are the knife K and the guide G. The knife is mounted on the end of a rotary shaft 10 supported in a bearing 11 in the frame of the machine, and it is actuated by any suitable means. Provision (not shown) is made for holding the knife shaft from longitudinal movement. The knife consists of a series of blades of substantially frusto-conical form, the edges of which blades are adapted to engage the material presented to them. The knife is driven at a high speed of rotation and cuts accurately and rapidly the material presented thereto.

The guide G consists of a member having a guiding edge 12 adapted to engage the bottom of the channel of the sole of a shoe, whether of the welt type as shown in the drawings, or of the McKay type. The edge

of the guide is adapted to run along on the outseam or in the groove in which the stitches of the outseam lie, and to hold the channel flap open, thereby preventing the channel flap from getting in the path of the cutter. The guide is formed on the end of a guide bar 13 provided on its under side with a rack which is engaged by a pinion 14 formed on the guide adjusting shaft 15 supported in a bearing in the sleeve 16, which in turn is secured to the bearing 11 by a set screw 17. By turning the guide adjusting shaft 15 the guide is moved out or in as desired to bring it to the proper position with relation to the knife. The guide is held in adjusted position by means of the spring washer 18, which is supported on the stem 19 of the guide adjusting shaft 15, and held in place by the nut 20. A handle 21 in the guide adjusting shaft 15 affords means for rotating the shaft to move the guide in or out. For the convenience of the operator in bringing the guide to the correct position, the guide adjusting shaft 15 is provided with a pointer 22, which by pointing to the different figures of the graduations 23, indicates the position of the guide. Thus the operative having a certain class of work to do may bring the guide to the adjustment which he knows by experience is the adjustment best adapted for the particular kind of work which he has to do. The knife is provided with a guard 24 practically semi-cylindrical in form, and projecting forward from the sleeve 16 over the knife. This guard is intended to safeguard the operative from accidental contact with the knife.

In operation, the shoe is presented to the machine so that the guide engages the bottom of the outsole channel and rides along at the base of the channel or on or near the seam. The guide is capable of being adjusted to move the work farther out or closer to the knife, as the style of cut determined upon requires. The operative then slides the shoe along the guide, observing the depth to which the knife is trimming. The operative may trim a portion off of the edge of the sole which gradually widens and then gradually tapers down again at the other end of the shank, and he determines the amount trimmed off by tipping the shoe more or less during the operation. Thus the machine lends itself

to the trimming of shoes widely differing from each other in shape, and by the simple expedient of tipping the shoe more or less during the time it is being presented to the knife. It is apparent that by tipping the shoe from the position shown in Fig. 3, a much larger portion of the edge of the sole could be removed, so that the sole would have the appearance of being very much thinner than the actual thickness, or on the other hand the sole could be trimmed as little as desired.

In its broader aspects the invention is not limited to the use of a rotary knife, nor to the details of construction above described, as the invention is susceptible of embodiment in other and different forms. It is preferred, however, to use a rotary knife, because it cuts with certainty and rapidity.

Having thus described the invention, what is claimed is:—

1. A shank trimming machine having, in combination, a work-guide having a portion adapted to engage the bottom of the outsole channel, and a trimming knife having its cutting portion adapted to trim off a portion of the edge of the sole, said guide constituting the only work guiding instrumentality and permitting movement of the shoe with relation to the guide and knife so that more or less material may be trimmed off of the sole edge, substantially as described.

2. A shank trimming machine having, in combination, a work-guide having a portion adapted to engage the bottom of the outsole channel, and a rotary trimming knife having its cutting portion adapted to trim off a portion of the edge of the sole, said guide constituting the only work guiding instrumentality and permitting movement of the shoe with relation to the guide and knife so that more or less material may be trimmed off of the sole edge, substantially as described.

3. A shank trimming machine having, in combination, a work-guide having a portion adapted to engage the bottom of the outsole channel, a trimming knife having its cutting portion adapted to trim off a portion of the edge of the sole, said guide constituting the only work guiding instrumentality and permitting movement of the shoe with relation to the guide and knife so that more or less material may be trimmed off of the sole edge, and means for adjusting the relative position of the guide and knife during the continued operation of the machine, substantially as described.

4. A shank trimming machine having, in combination, a work-guide having a portion adapted to engage the bottom of the outsole channel, a trimming knife having its cutting portion adapted to trim off a portion of the edge of the sole, said guide con-

stituting the only work guiding instrumentality and permitting movement of the shoe with relation to the guide and knife so that more or less material may be trimmed off of the sole edge, and means for adjusting the relative position of the guide and knife, substantially as described.

5. The combination with a work guide arranged to engage a shoe sole, of a sole trimming knife, a slide carrying the work guide adjustable longitudinally to change the position of the guide with relation to the knife and provided with a rack, an actuating pinion engaging the rack, and means for indicating the position of the guide comprising a pointer operatively connected to the pinion and a series of graduations co-operating with the pointer, substantially as described.

6. A shank trimming machine having, in combination, a rotary knife having its cutting portion adapted to trim off a portion of the edge of the sole, a work-guide having a portion adapted to engage the bottom of the outsole channel, and a work-guide slide for carrying the guide supported in position to be moved in a direction parallel to the axis of the knife, substantially as described.

7. A shank trimming machine having, in combination, a work-guide having a portion adapted to engage the bottom of the outsole channel, and a frusto-conical rotary trimming knife having its cutting portion adapted to trim off a portion of the edge of the sole and having its axis at right angles to the tread surface of the sole when in position to be trimmed, substantially as described.

8. A shank trimming machine, having, in combination, a trimming knife having its cutting portion adapted to trim off a portion of the edge of a shoe sole, a guide mounted rigidly with relation to the knife and having a portion adapted to engage the channel of the outsole while on the shoe, and means for adjusting the relative position of the knife and guide, substantially as described.

9. A shank trimming machine, having, in combination, a trimming knife adapted to trim a portion of the edge of a shoe sole and a work guide supported independently of the knife and adapted to engage the channel of the outsole while on the shoe, substantially as described.

10. A shank trimming machine, having, in combination, a trimming knife adapted to trim off a portion of the edge of a shoe sole, a guide arranged to engage the channel of the outsole while on the shoe and means for adjusting the guide with relation to the knife, substantially as described.

11. A shank trimming machine, having, in combination, a trimming knife adapted to trim off a portion of the edge of a shoe sole, and a stationary guide mounted rigidly with

relation to the knife and arranged to engage the channel of the outsole while on the shoe, substantially as described.

12. A shank trimming machine, having, in combination, a rotary knife having its cutting portion adapted to trim off a portion of the edge of the sole, and a work guide supported independently of the knife arranged to engage the channel of the outsole

while on the shoe at a point in line with the 10 axis of the knife transversely of the direction of feed, substantially as described.

In testimony whereof I affix my signature, in presence of two witnesses.

GEORGE GODDU.
